UNITED STATES PATENT OFFICE

NATHAN C. PHILLIPS, OF GLOUCESTER, MASSACHUSETTS, ASSIGNOR TO RUSSIA CEMENT COMPANY, OF GLOUCESTER, MASSACHUSETTS

DESIGN FOR A BOTTLE

Application filed August 1, 1931. Serial No. 40,755. Term of patent 14 years.

To all whom it may concern:

Be it known that I, NATHAN C. PHILLIPS, a citizen of the United States, residing at Gloucester, in the county of Essex and State of Massachusetts, have invented a new, original, and ornamental Design for Bottle, of which the following is a specification, reference being had to the accompanying drawing, forming part thereof.

The view is a side elevational view of my new design.

I claim:

The ornamental design for a bottle, as shown.

NATHAN C. PHILLIPS.
